UNITED STATES PATENT OFFICE.

CHARLES J. VAN DEPOELE, OF LYNN, MASSACHUSETTS.

ELECTRIC MOTOR.

SPECIFICATION forming part of Letters Patent No. 443,980, dated December 30, 1890.

Application filed March 8, 1889. Serial No. 302,544. (No model.)

To all whom it may concern:

Be it known that I, CHARLES J. VAN DEPOELE, a citizen of the United States, residing at Lynn, in the county of Essex and State of Massachusetts, have invented certain new and useful Improvements in Electric Motors, of which the following is a description, reference being had to the accompanying drawings, and to the letters and figures of reference marked thereon.

My invention relates to an improvement in electro-dynamic motors; and it comprises a rotating electro-magnetic motor or engine applicable to any form of work and capable of being operated in some of its forms by any species of current, whether pulsating or intermittent. Since many forms of electric motors are capable of operation with continuous currents, I will describe the invention more particularly with reference to its operation under the influence of alternating, intermittent, or pulsating currents. It is well known that almost any form of dynamo-electric machine having its iron parts sufficiently subdivided to respond to rapid reversals of polarity is capable of being set in motion by alternating electric currents; but such machines are not capable of efficient action until the armature speed corresponds with or is in synchronism with that of the generator supplying the current, therefore the torque of such a motor is very feeble at starting, and it has been hitherto found impracticable to apply alternating currents to motors where they were required to run at low speed or start a load—as, for example, in electric-railway work, where the motors are frequently stopped and started with the full load.

My improved motor comprises an armature which may be of any of the well-known types, including a wire-wound iron core; but I prefer to use a Gramme ring, the terminals of the sections of which may be connected in various ways, as will appear. The armature rotates under the action of a field of force in the usual manner. In addition to the armature and field magnets I use a third element in the form of a non-rotating coil or coils of insulated wire, the said coils enveloping or partially enveloping the armature and acting inductively thereon to produce in the armature

a definite and concentrated polarity—that is, true poles adapted to cause the rotation of the armature under the influence of the field-magnet. It has been proposed to cause the rotation of an armature by currents induced therein while rotating in its field of force; but while this may produce practical results when the armature is rotating at high speed, its effect is almost *nil* at starting, and various extraneous means have been proposed for creating magnetism in the armature-core at starting. By my invention, however, these difficulties are entirely overcome and the motor is rendered as efficient at low speed and at starting as any continuous-current machine, and without any reference whatever to the rate of the phases of supply-current.

The invention may of course be applied and modified in a great variety of ways, some of which are shown in the accompanying drawings and set forth and referred to in the following description and the claims appended thereto.

In the drawings, Figure 1 is a view in elevation of a motor embodying my invention. Fig. 2 is a diagrammatic view of the motor, showing circuits and regulator. Fig. 3 is a diagrammatic view similar to Fig. 2, but showing a different arrangement of circuits. Fig. 4 is a view in elevation, partly in section, showing a somewhat different arrangement of the moving parts. Fig. 5 is an elevation showing a construction and arrangement differing in some respects from that seen in Fig. 4. Fig. 6 is a view in elevation, partly in section, of another arrangement of parts of the motor also embodying the invention. Figs. 7 and 8 are diagrammatic views illustrating different modes of regulating and controlling the action of the motor. Fig. 9 is a view in elevation, partly in section, showing a motor of the same general form, the connections and manner of energizing the armature being somewhat different. Fig. 10 is also a view in elevation, partly in section, but showing a somewhat different arrangement of the armature-winding.

As indicated in the drawings, with reference to Fig. 1 and other similar figures not specifically mentioned, A A' represent oppositely-located field-magnets, the polar exten-

sions $a a' a^2 a^3$ of which are magnetized by coils $B B'$, wound upon laminated iron cores extending between and connecting the polar extensions.

5 C is an iron ring constituting the core of the armature D, which is wound with a continuous conductor C'. As shown, the coils of the armature D are connected by conductors $d d'$, extending across at right angles with each other and electrically uniting diametrically-opposite portions of the armature-conductor to form two closed circuits therein. In large armatures it will frequently be desirable to use more cross-connections than the two here shown, but they will serve to illustrate the principle. The armature is partly enclosed within a non-rotating exterior induction-coil E, which is placed about its transverse axis, the normal position of the coil E being at right angles to the axis of the field-magnets. For convenience, as here shown, the induction-coil E is sustained within recesses formed at the neutral points of the field-magnet; but it may also be entirely within the field-magnet and movably sustained in the desired position.

As shown, the coils of the field-magnets A A' and the coil E are connected in series, the current entering coil B' by conductor 1, passing thence by conductor 2 to coil B, thence by conductor 3 to solenoid E, and from thence to line by conductor 4. Current flowing through said coils will magnetize the polar extensions, as indicated by the signs thereon, while the coil E will, when an alternating or pulsating current is employed, act inductively upon the armature, causing secondary currents to flow therein. The secondary currents, having a defined path by reason of the cross connections $d d'$, will concentrate their magnetizing effect and form true poles along the lines represented by said cross-conductors, and whether the armature be held stationary or be in motion the poles so established in the armature will be strongly attracted by their opposite poles on the field-magnets and repelled by like ones. Thus it will be seen that the action of my motor while depending upon the magnetization of the armature from currents induced therein is not dependent upon the rapid rotation of said armature for its efficiency, since the same inductional effects will take place when the armature is forcibly prevented from rotating.

55 In Fig. 2 an arrangement similar to the foregoing is represented, diagrammatically, but I have shown a regulator in the form of reactive coil F included in a derivation from the series circuit.

60 In Fig. 3 I have shown a view similar to Fig. 2, except that the circuit 7 8 of the coil E and of the field-magnets A A' by conductors 5 6 are entirely separate and each one provided with a reactive coil $F' F^2$ for controlling the flow of current in their respective circuits. The reactive coils can be solenoids provided with movable iron-cores f ,

which when entirely inserted in the coils create a reaction therein, which by creating a counter-electro-motive force in said coils opposes the flow of the main current therethrough. As the cores f are withdrawn the reactions are diminished and a convenient means for controlling the flow of current is thus afforded. When two such circuits are placed in parallel, either one or the other can be made to predominate to produce the desired effects.

In Fig. 4 is seen an annular exterior field-magnet G, having two energizing-coils $g g'$, which are separated at their extremities to expose the positive and negative poles $g^2 g^3$ in the iron core. The armature D' is mounted within the field-magnet, and the induction-coil E' is located between the exterior of the armature and the interior of the field-magnet. In this case, also, the armature is shown as an ordinary Gramme ring, but each section is provided with a terminal e , connected to a corresponding section of a commutator H. A pair of oppositely-mounted and adjustable commutator-brushes are held in any desired position with respect to the commutator, and when electrically connected serve to close the commutator-circuit upon itself, thereby causing currents flowing in the armature to traverse a defined path and to establish true poles therein upon the line occupied by the commutator-brushes. It may be desirable for more thorough regulation and control to connect an adjustable resistance between the commutator-brushes. As shown, the positive commutator-brush h is connected by conductor h' with the switch-lever h^2 of an adjustable resistance I, the other extremity of the resistance I being connected by conductor i to commutator-brush i' . The induction-coil E' acts inductively upon the coils of the armature D', generating currents therein, which, flowing around said armature and along the line established by the commutator-brushes and circuit-connections, will establish a polarity in the said armature, which, being at an angle from the poles of the field-magnet, will be attracted thereby and the armature thus set in motion. By changing the position of the commutator-brushes the polar axis of the armature can be moved as desired to secure the best working effect under varying circumstances, the normal position being, however, at right angles to the polar axis of the field-magnet, as indicated.

I have referred to the coils acting upon the armature as an induction coil or coils. It will be understood, however, that the said coil may be formed in two or more parts, according to the mechanical exigencies of the case. Wherever movable commutator-brushes are used it will also be desirable that the position of the induction-coil be movable—that is to say, that, although it must not rotate as does the armature, the best effect will be secured by keeping its axial line always at right

angles with the desired polar axis of the armature. The form shown in Fig. 4 may be readily subdivided to produce a four or more pole machine.

5 As seen in Fig. 5, the field-magnet G' is provided with four oppositely-located polar extensions between which the magnetizing-coils b' b² b³ b⁴ are wound. The armature D' is similar to that seen in the preceding figure, 10 as also is its induction-coil E'. Since, however, the field-magnet is provided with four poles a double set of poles must also be formed in the armature, which is accomplished by providing the commutator H' thereof with two sets 15 of commutator-brushes J J' J² J³. The said brushes are attached at right angles and are movably mounted upon a stationary part of the machine and provided with an operating-lever J⁴, by which they may be adjusted about 20 the commutator as desired. The induction-coil E' is also sustained by a stationary portion of the machine and connected or attached to the commutator-brush carrier, so that both move together, thus insuring sym- 25 metrical relationship between the magnetic axis of the induction-coil and the polar lines it is desired to establish in the armature. Opposite commutator-brushes are connected by conductors j j', thus forming two closed 30 circuits in the armature, and consequently two polar axes therein, which, as indicated, are at right angles to each other. It will be understood that the induction-coil as an entirety can be connected so as to produce four 35 poles in the armature; but the better way is to arrange the connections to form two inducing-circuits to maintain the four armature-poles. With this form the most economical 40 action will take place when the axis of the induction coil or coils and of one pair of commutator-brushes is upon the line x x'. Although desirable for purposes of regulation, it is not necessary that any exterior resistance 45 be placed in the short circuit connecting the commutator-brushes.

In Fig. 4 the coils of the field-magnets and of the induction-coils are in separate circuits. 50 9 and 10 represent one set, and 11 12 the other set, of terminals of the field-magnet coils g g', which, being united with their line conductors, place the coils g g' in multiple arc. The induction-coil E' receives current through conductors 13 14, either from a separate circuit or from a source local to the motor. In 55 Fig. 5 the coils of the field-magnets and of the induction coil or coils E' are all connected in multiple arc. The current entering at 15 divides through conductors 16 17, passing to the field-magnet coils and to the solenoid 60 traversing same, and passing out by conductors 18 19, and thence to line-conductor 20.

Various different methods of regulating the flow of supply-current in the field-magnet circuit and induction-coil may be adopted.

65 In Fig. 7 the apparatus is indicated diagrammatically and an artificial resistance I' is shown in a derivation from the field-mag-

net circuit. It will be clear, however, that the adjustable resistance might be connected in a derivation from the induction-coil or a 70 separate resistance be used in connection with both the field-magnet circuit and the induction coil or coils.

In Fig. 8 I show a reactive coil F in derivation from the field-magnet circuit. The field-magnet coils and those of the induction-coil are connected in series.

Instead of connecting all the coils of the armature into one or more circuits closed upon themselves, I may employ the arrangement 80 shown in Fig. 6, in which the field-magnet circuit and induction-coils are similar to that seen in Fig. 1. The coils of the armature J² are, however, somewhat differently connected. Alternate sections L are connected by conductors l l' to separate sections of a commutator H² in the same manner as the sections of the Gramme ring. Commutator-brushes J⁴ J⁵ bear upon opposite sides of the commutator and are provided with conductors 21 90 22, connected in derivation from the main supply-circuit of the machine.

A reactive coil F is connected in series with the supply-circuit, the course of which is as follows: The current enters by conductor 95 23, passing through reactive coil F, and thence by conductor 24 to the field-magnet coil B. From said coil current passes by conductor 25 to the other field-magnet coil B', thence by conductor 26 to point 27, from where the main 100 current passes by conductor 28 to the coil E, leaving the said coil by conductor 29, which is connected to the other side of the circuit at 30. The conductor 22, representing one of the commutator-brushes, is connected to the 105 conductor 26 at the point 27, and the return-conductor 21, from the other commutator-brush, is connected to the other side of the circuit at point 30. The field-magnet coils and those of the induction-coil are therefore 110 connected in series with the armature-circuit in derivation therefrom. Coils M are placed between each of the coils L on the armature, and each coil M is closed upon itself. The induction-coil E will act inductively upon the 115 coils M and thereby add to the magnetizing effect of the coils L, which are connected in the main circuit. It will be obvious that by disconnecting the conductors 21 and 22 from the main circuit and uniting them the same 120 effect would be produced as described with reference to Fig. 4, with the addition of the magnetizing effect upon the core of the armature B² produced by the additional coils M.

Fig. 9 represents a modification of the specific forms already referred to in the matter of connecting the armature-coils. Instead of bringing all or part of the terminals of the successive coils to a commutator, as in a Gramme or Pacinotti armature, thus connecting all the sections in one continuous circuit, I wind the core N with a number of separate coils n, or even a single copper ring, according to the size of the armature, each coil

being closed upon itself and well insulated from its neighbors. By this disposition the action of the inducing-coil E^2 upon the coils n will produce currents flowing on the right side of the armature, say, from bottom to top in the said coils and on the left side from top to bottom. This is due to the fact that the coils on the right side, say, present all their inner closed terminals upward and their outer terminals downward, the reverse being the case with the coils upon the other side of the armature, so that under these conditions the current induced by the solenoid will produce a north pole on the top of the armature and a south pole on the bottom, and these conditions will obtain whether the armature be at rest or rotating at any speed. The field-magnets of my motor may be constructed of forms and arranged differently from those heretofore described—as, for example, in said Fig. 9 the polar extensions $O O'$ are semicircular in form and envelop the induction-coil E^2 and most of the armature, being separated at their extremities. From the extremities of the pole-pieces $O O'$ extend cores O^2 and P and O^3 and P' , each of which is provided with a magnetizing-coil p , acting to produce north poles at each extremity of the pole-piece O' and south poles at the extremity of the pole-piece O . With this arrangement the positive pole at the top of the armature will be repelled by the adjacent north pole in the field-magnets and attracted toward the adjacent south pole of the field-magnets, while the south pole at the bottom of the armature will be repelled by the adjacent south pole, thus establishing and maintaining rotation in the armature so long as the same is magnetized by the inductional effects upon its coils of the induction-coil E^2 . The field-magnet coils and the induction-coil seen in Figs. 9 and 10 may be connected in any of the different ways hereinbefore referred to. As seen, however, they are provided with separate circuits, represented by terminals 31, 32 and 33, 34.

As indicated in Fig. 9, the coils of the armature are almost entirely enveloped by the inducing-coils B^3 . There will still be, however, some current developed in the coils passing between the poles of the field-magnets by the action of the field-magnets thereon, and these currents being in an opposite direction from the currents induced by the induction-coil will tend to diminish the desired magnetizing effect. This will not amount to very much where the induction-coil is of the proportions indicated in said figure; but, whatever their quantity, the production of said opposing currents may, when desired, be entirely prevented by cutting out the coils passing between the field-magnet poles, allowing them to pass those points in an entirely inactive condition. This may be accomplished in many different ways—for example, as indicated in Fig. 10, where the coils m are each provided with a free terminal Q , provided with a contact device or

brush q , the other extremities of all the coils being connected to and united by a conductor R . Fixed segments $R' R^2$ are arranged to engage and thereby connect in multiple arc the terminals q of the coils on each side of the armature which are under the influence of the induction-coil E^2 , but not to engage the terminals of the coils passing under the influence of the poles of the field-magnet, they being open-circuited and entirely inactive. The segments $R' R^2$ are electrically connected by conducting strips $r r'$, and currents induced in the coils under the influence of the induction-coil on one side of the armature flow in multiple arc to the segment R^2 , for example, thence by conductors $r r'$ to the segment R' , thence by the terminals q of the corresponding coils upon that side of the armature and out of said coils into the conductor R , and by said conductor to the inner terminals of the coils upon the opposite side of the armature, substantially as indicated by the arrows. Any kind of commutation will answer, the form shown being by way of illustration.

As indicated in Figs. 9 and 10, the armature-shaft S is provided with a hub S' , from which extend non-metallic spokes or arms T , which, being mechanically attached to the core N between the coils m or n , form a strong and symmetrical support therefor.

Having described my invention, what I claim, and desire to secure by Letters Patent, is—

1. An electro-dynamic motor for alternating or pulsating currents, comprising a wire-wound armature, an electro-magnetic system surrounding the armature, for producing magnetizing-currents therein by induction, thereby establishing poles in said armature, and a field-magnet arranged to react upon the armature-poles produced by the induction system.

2. An electro-dynamic motor for alternating or pulsating currents, comprising a wire-wound armature and a separate stationary electro-magnetic system surrounding the armature, for producing magnetizing-currents therein by induction and thereby establishing poles in said armature, and a field-magnet arranged to react upon the poles of the armature produced by the said induction system.

3. An electro-dynamic motor for alternating or pulsating currents comprising a wire-wound armature and a surrounding induction-coil for producing currents therein by induction to form poles of dissimilar name on opposite sides of the armature, and a field-magnet for reacting upon the poles so produced in the armature, substantially as described.

4. An electro-dynamic motor for alternating or pulsating currents, comprising a wire-wound armature, a stationary induction-coil surrounding and inducing magnetizing-currents in the armature to produce polarities of opposite name in said armature and at right

angles to the line of the axis of the magnetizing-coils, and suitable field-magnets reacting upon the armature at an angle to the poles produced by the said induction system, substantially as described.

5. An electro-dynamic motor for alternating or pulsating currents, comprising a wire-wound armature having one or more closed circuits, a surrounding stationary coil or coils 10 inducing magnetizing-currents in the armature, and a suitable field-magnet for reacting upon the armature-poles produced by the stationary coil or coils.

6. An electro-dynamic motor comprising a 15 wire-wound armature, means for connecting the armature-conductor into one or more circuits, a surrounding stationary coil inducing magnetizing-currents in the armature, and a field-magnet reacting upon the poles of 20 the armature.

7. In an electro-dynamic motor and armature wound with circuits closed upon themselves, an exterior coil for inducing magnetizing-currents therein, a field-magnet for 25 acting upon the poles of the armature, produced by the currents induced therein by the stationary coil, and means for shifting and adjusting the polar line or lines of the armature with respect to the poles of the field-magnets, as desired.

8. In an electro-dynamic motor, a wire-wound armature connected to form one or more closed circuits, and a non-rotating adjustable electro-magnetic system surrounding 35 and inducing magnetizing-currents in the armature-conductor to form poles therein upon the line of the magnetic axis of the inducing system, and a suitable field-magnet.

9. In an electro-dynamic motor, a wire-wound armature connected to form one or more closed circuits, a stationary field-magnet for reacting thereon, and a non-rotating coil adjustable with respect to the poles of the field-magnets and acting inductively upon the 45 armature-conductor to produce magnetizing-currents therein and establish armature-poles upon the line of its magnetic axis.

10. In an electro-dynamic motor, a wire-wound armature comprising one or more 50 closed circuits, a field-magnet for reacting upon poles in the armature, and separate means, comprising an induction coil or coils surrounding the armature, for inducing interrupted magnetizing-currents in the circuit 55 or circuits of the armature-conductor.

11. In an electro-dynamic motor, a wire-wound armature comprising one or more closed circuits, a stationary field-magnet acting upon the armature and energized by intermittent, pulsating, or alternating currents, 60 and separate means for inducing magnetizing-currents in the circuit or circuits of the armature, comprising a coil or coils surrounding the same and acting under the influence of the supply-currents.

12. In an electro-dynamic motor, the combination of a wire-wound armature comprising one or more closed circuits, a stationary field-magnet therefor, means for controlling the phase of current therein, and a coil or 70 coils exterior to the armature-conductor and acting thereon to produce magnetizing-currents by induction.

13. An electro-dynamic motor comprising a wire-wound armature having one or more 75 closed circuits therein, a stationary field-magnet and an exterior coil or coils acting inductively upon the armature-conductor to produce magnetizing-currents in the armature-circuits, and adjustable means for controlling the flow or phase of current in the inducing-coils.

14. In an electro-dynamic motor, a wire-wound armature comprising one or more closed circuits, a stationary field-magnet 85 therefor, means for regulating the flow or phase of current in the coils thereof, an exterior coil or coils acting inductively upon the armature and producing magnetizing-currents therein, and means for regulating the 90 flow and phase of current in the said coils with respect to the field-magnet circuit.

15. In an electric motor, an armature wound with circuits closed upon themselves, a stationary coil acting inductively upon the armature, a field-magnet for said armature, a divided alternating circuit placed, respectively, upon the induction system and the field-magnets and supplied with currents of 95 alternating polarity, and means for regulating the phases of current in the several circuits.

In testimony whereof I hereto affix my signature in presence of two witnesses.

CHARLES J. VAN DEPOELE.
